UNITED STATES PATENT OFFICE.

OSCAR A. SMITH AND BENJAMIN F. RINDFLEISCH, OF CLEVELAND, OHIO, ASSIGNEES
TO THE NATIONAL-ACME MANUFACTURING COMPANY, OF CLEVELAND, OHIO, A
CORPORATION OF OHIO.

DIE.

1,157,259.

Specification of Letters Patent.

Patented Oct. 19, 1915.

Original application filed July 21, 1914, Serial No. 852,168. Divided and this application filed December 10, 1914. Serial No. 876,407.

To all whom it may concern:

Be it known that we, OSCAR A. SMITH and BENJAMIN F. RINDFLEISCH, citizens of the United States, residing at Cleveland, in the county of Cuyahoga and State of Ohio, have invented certain new and useful Improvements in Dies, of which the following is a specification.

This invention relates to dies for use in the castellation of nuts adapted for use in presses such for instance as that shown in our contemporaneously pending application Serial No. 852,168, filed July 21, 1914, of which the present application is a division, the object of the invention being to provide an improved die which will automatically clear itself, and an improved die carrier for such die.

Another object of the invention is the provision of means for holding the nut in proper relation to the slots in the die after it is punched and during successive punching operations.

Another object of the invention is the provision of a reinforced die having a plurality of slots corresponding in number with the number of slots which it is desired to punch in the nut, and which nut will be revolved with the die.

Another object of the invention is the provision of means for protecting the punch used in connection with this improved die from the slugs punched from the nut.

In the drawings accompanying and forming part of this specification, Figure 1 is a front view of the die and one of its locking means; Fig. 2 illustrates the various members of the die and its carrier; Fig. 3 is an enlarged sectional view of a part of the ring shown at the left of Fig. 2; Fig. 4 is a perspective view of a castellated nut; and Fig. 5 is a sectional view illustrating the die in use in connection with a nut castellating press and punch and showing the position of the die relatively to the feed plunger and punch.

Similar characters of reference indicate corresponding parts in the different figures of the drawings.

This improved die 2 is provided with as many slots 3 as it is desired to punch in the nut or other piece to be slotted, these slots communicating with an axial opening or bore 4 in the die which receives the nut

blank in the manner hereinafter described. 55 These radial slots are formed in an annular projection or what may be called a hub 5 of the die, and at their outer ends the slots communicate with an annular recess or clearance way 6, so that the slugs punched 60 out of the nut or other piece being operated upon, the punch working, it will be understood, from the center of the hole in the nut outwardly and through a slot in the die, will drop clear of both the punch and the 65 die by reason of this clearance way. To insure that the slugs are not retained inside the groove or clearance way of the die and so be carried up and drop into the inside of the die and interfere with the punch during 70 the indexing of the die, a guard 7 of any suitable form may be used. In the present instance this guard is adapted to fit loosely over the punch, and for this purpose is provided with a key-hole slot 8 for the reception of the end of the punch, and this guard is so located that there is just sufficient room for clearance between the face of the punch arm and the guard and between the guard and the face of the die. The die is also provided with a peripheral annular projection or rim 9, and this die sets into a ring 10, which is provided with as many indexing and locking recesses or grooves 11 as there are slots in the die. In other words, the 85 number of grooves or recesses in the ring corresponds with the number of slots in the die, and of course these slots correspond in number with the number of slots that the nut is to have. The die and the ring, which 90 will hereinafter be called the index ring, since it is by this means in part that the die is indexed, are maintained in proper relation by means of a locating pin 12 (see Fig. 5) fitting into registering grooves of 95 the ring and die respectively. A holder plate or ring 13 is provided for holding the die in position in the ring 10, and for this purpose the holder plate is provided with a plurality of elongated slots 14 for the reception of bolts 15 which pass into the index ring 10. As the nut blanks are fed into position for slotting they pass through the axial opening in the holder plate 13, and this holder plate is provided with nut positioning or gripping means in the form of 100 a pair of spring tensioned jaws 16 dovetailed into the holder plate, and tension on these

jaws is obtained by expansion springs 17 (see Fig. 3) placed within a recess in the holder plate and having a bearing at one end on a screw in the end of said recess and at 5 its opposite end on a stud 19 carried by said jaws and projecting into the recess, and this holder plate is fastened by means of the bolts 15 hereinbefore referred to, to the front face of the index ring 10 and revolves 10 with it. The index ring is carried by a steel bearing ring 20, which is supported in a bracket 21, shown in section in Fig. 5, and which ring is effective to take up any 15 wear that may occur between the index ring 10 and the holder plate 13. The holder plate 13 is adjustable by means of the elongated slots 14 hereinbefore referred to, whereby the spring jaws 16 will be properly positioned, so that the nuts or other blanks 20 being fed through the jaws thereof will come in exact alinement with the punch and die when the die is locked in position. As the nuts or other pieces are forced between the jaws 16 these jaws may expand slightly 25 to permit of the passage of a corner of the nut should it not be fed exactly straight with the face of the jaw, but the springs are strong enough to straighten the piece and to make a flat bearing between the face of the 30 jaw and the side of the blank or nut.

We claim as our invention:

1. A die comprising a disk having a bore provided with a projecting hub having a plurality of equally spaced slots each extending radially entirely through the hub. 35
2. A die comprising a disk having a bore provided with a projecting slotted hub and a clearance way surrounding said hub.
3. A die comprising a disk having a flanged periphery and a bored hub extending in the same direction as the flange and having slots communicating with the bore. 40
4. A die comprising a disk having a flange periphery and a bored hub extending in the same direction as the flange and having slots communicating with the bore, and a clearance way between said hub and peripheral flange, said flange having a location slot in its periphery. 45
5. A die comprising a slotted disk, a die carrier having slots corresponding in number with the slots of the die for permitting the indexing of said die, and means for securing the die within said carrier. 50
6. A die comprising a slotted disk, a die carrier having slots corresponding in number with the slots of the die for permitting the indexing of said die, adjustable means for holding the die within said carrier, and nut positioning means carried by said adjustable means. 60
7. A die comprising a disk having a projecting slotted hub and a flanged periphery and provided with a clearance way between said hub and flange, a die carrier having 65

slots corresponding in number with the slots in said hub for permitting the indexing of the die, and means for securing said die within the carrier.

8. A die comprising a disk having a projecting slotted hub and a flanged periphery and provided with a clearance way between said hub and flange, a die carrier having slots corresponding in number with the slots in said hub for permitting the indexing of the die, adjustable means for holding said die within the carrier, and nut positioning means carried by said adjustable means. 70

9. A die comprising a disk having a peripheral flange and a slotted projecting hub separated from said flange by a clearance way, a die carrier provided with slots corresponding in number with the slots in said hub, a bearing member adapted to receive said carrier, and means for securing all of 75 said members together. 80

10. A die comprising a disk having a peripheral flange and a slotted projecting hub separated from said flange by a clearance way, a die carrier provided with slots corresponding in number with the slots in said hub, a bearing member adapted to receive said carrier, adjustable means for holding all of 85 said members together, and nut positioning means carried by said adjustable means. 90

11. A die comprising a disk having a peripheral flange and a slotted projecting hub separated from said flange by a clearance way, a protecting member adapted to rest 100 against the face of said hub and having a slot adapted to register with any one of the slots in said hub, and a die carrier provided with slots corresponding in number with the slots in said hub. 105

12. A die comprising a disk having a peripheral flange and a slotted projecting hub separated from said flange by a clearance way, a protecting member adapted to rest against the face of said hub and having a slot adapted to register with any one of the slots in said hub, a die carrier provided with slots corresponding in number with the slots in said hub, and a bearing member adapted to receive said carrier. 110

13. A die comprising a disk having a peripheral flange and a slotted projecting hub separated from said flange by a clearance way, a protecting member adapted to rest against the face of said hub and having a slot adapted to register with any one of the slots in said hub, a die carrier provided with slots corresponding in number with the slots in said hub, a bearing member adapted to receive said carrier, and means for securing said die, die-carrier and bearing member together. 115

14. A die comprising a disk having a peripheral flange and a slotted projecting hub separated from said flange by a clearance way, a 120

- way, a protecting member adapted to rest against the face of said hub and having a slot adapted to register with any one of the slots in said hub, a die carrier provided with 5 slots corresponding in number with the slots in said hub, a bearing member adapted to receive said carrier, adjustable means for holding said die, die-carrier and bearing member together, and nut positioning means 10 comprising a plurality of spring jaws carried by said adjustable means.
15. A die comprising a disk having a peripheral flange and a slotted projecting hub separated from said flange by a clearance 15 way, a die carrier provided with slots corresponding in number with the slots in said hub, a bearing member adapted to receive said carrier, and means for securing all of said members together, said means 20 comprising a ring and screws passing through said ring and into said carrier.
16. A die comprising a disk having a peripheral flange and a slotted projecting hub separated from said flange by a clearance 25 way, a die carrier provided with slots cor-
- responding in number with the slots in said hub, a bearing member adapted to receive said carrier, adjustable means for holding all of said members together, said means comprising a ring provided with elongated 30 slots and screws passing through said slots and into said carrier and spring jaws carried by said ring.
17. A die comprising a slotted disk, a die carrier therefor, and nut positioning means 35 carried by said die carrier.
18. A die comprising a slotted disk, a die carrier therefor, and nut positioning means carried by said die carrier, said nut positioning means comprising a plurality of spring 40 tensioned jaws.

Signed at Cleveland, in the county of Cuyahoga and State of Ohio, this 8th day of December, 1914.
